TELEPHONE SYSTEM

John William McClew, Liverpool, and Owen Avis Pearce, Barnston, England, assignors to Associated Telephone & Telegraph Company, Chicago, Ill., a corporation of Delaware

Application September 12, 1938, Serial No. 229,502
In Great Britain September 17, 1937

15 Claims. (Cl. 179—26)

The present invention relates to telephone systems and is more particularly applicable to semi-automatic telephone systems such as are used in rural areas. In such areas the telephone exchanges involved may include a main exchange, a few satellite exchanges and numerous small exchanges of the semi-automatic remotely-controlled type which will hereafter be referred to as R. C. X.'s. A typical layout for such an area is described in the application of C. E. Beale, I. T. Richards and O. A. Pearce, Serial No. 230,416, filed Sept. 17, 1938, in which one radiating branch from the main exchange is assumed to include a tandem satellite exchange, a tandem R. C. X. and a terminal R. C. X.

The arrangement is that the subscribers on the main exchange and tandem satellite exchange are provided with dial telephones and are permitted to set up calls to other subscribers on their own exchange automatically, but for all external calls the subscribers must dial a distinctive digit which routes the connection to the manual board at the main exchange, from which the operator controls automatic switches in the one or more exchanges involved in routing the call to its required destination.

The subscribers on the tandem and terminal R. C. X.'s are not provided with dial telephones and on all calls they must signal the operator at the manual board who after ascertaining the number of the wanted party controls automatic switches to set up the connection automatically. In case the wanted party is connected to an exchange on the same radiating branch from the main exchange as that over which the call was originated, the operator must be enabled to dial back over the junction route taken into use by the calling party so as to gain access to any of the exchanges connected thereto, the apparatus taken into use at the originating exchange by the calling party having to be held during this time. After the setting up of the connection to the wanted party, the operator withdraws her plug and the two subscribers are then either linked together locally in the originating exchange in the case of a call for a local subscriber or alternatively they are linked together over the junction or junctions connecting the two subscribers' exchanges together.

The general object of the invention is to provide improved signalling and line testing facilities in areas of the above type, use being made of high voltage responding devices employing gas discharge tubes.

In the above circumstances difficulties arise where for example it is desired to perform from the main exchange a fault routine test on the subscribers' lines of the exchanges connecting therewith since only the ordinary selector train can be utilised. It is unlikely that it would ever

be an economical proposition to provide special testing junctions and switches for this purpose and it is one object of the invention to provide arrangements whereby normal service junctions can be utilised for the setting up of line test connections.

According to one feature of the invention in a telephone system including a plurality of exchanges and having calls for a party connected to one exchange set up over automatic switches within that exchange from an operator's position located in another exchange to which a calling party is automatically connected, in order to permit testing of a subscriber's line to be carried out over a connection set up from the exchange in which the operator's position is located a relay connected to the line in series with a gas discharge tube is adapted to be operated in response to a pulse of high voltage and thereupon to cut out the feeding bridges and transmission condensers and give a metallic loop.

It will be understood that an arrangement of this type is associated with each transmission bridge in the connection extending between the test desk and the desired line and according to another feature of the invention, in a telephone system including a plurality of exchanges connected in tandem and arranged for signals to be transmitted by the connection of a high voltage to the line, a signal causes the operation of a relay connected in series with a gas discharge tube, the operation of the relay serving to cut out the feeding bridges and transmission condensers so that the high voltage signal is extended to a succeeding exchange to effect a switching operation thereat.

Furthermore it is usually arranged that when an R. C. X. subscriber originates a call he gives to the main exchange operator both his own number for fee allocation purposes and the wanted party's number. It is desirable however to provide arrangements whereby the main exchange operator can verify the number given by the calling party in order to prevent fraud particularly where a long distance call is required. This is conveniently effected by setting up a checking connection back over the junction utilised by the calling party to the line the number of which has been given to the operator and if the operator receives busy tone it may be assumed that the calling party has given his correct number, particularly if only one junction is provided, or alternatively if the operator desires a more definite check she may cut-in on the engaged line and ask the number of the subscriber. It is now necessary to release the checking connection set up at the R. C. X. whether the call is to be set up locally or extended to a distant exchange and it is another object of the invention to provide improved arrangements whereby this may be simplified.

ply effected, it being realised that ordinary direct current signalling arrangements cannot readily be adopted since they are already utilised for other purposes.

5 A further feature of the invention is that both the above mentioned facilities are provided in that in a telephone system including a plurality of exchanges connected in tandem to an exchange provided with an operator's position, a high 10 voltage signal transmitted from the exchange in which the operator's position is located is arranged according to its polarity to operate a relay connected in series with a gas discharge tube to effect either the cutting out of feeding bridges and 15 transmission condensers or the release of a connection in any of the tandem connected exchanges.

According to another feature of the invention in a telephone system including a plurality of 20 exchanges at one of which an operator's position is located, calls from the other exchanges are automatically extended to the operator's position whence a connection is set up to the number given by the calling party as his own, the 25 numerical switches in the originating exchange which are set to complete this verifying connection being subsequently released in response to the transmission of a high voltage pulse to effect the operation of a relay connected to the line in 30 series with a gas discharge tube whereby the same numerical switches may be used for setting up the wanted connection without the original connection to the operator being released.

The invention will be better understood from 35 the following description of one method of carrying it into effect, reference being had to the accompanying drawings comprising Figs. 1-11 which should be arranged in the manner shown in Fig. 12 to form a complete circuit diagram. 40 This shows an R. C. X. board having tandem facilities and with provision for one incoming main exchange junction and for up to ten lines which include local lines and also a line to an adjacent R. C. X. if the board is functioning in a 45 tandem capacity. One link circuit employing a 12-point line finder switch of the reverse drive uniselector type and a similar connector switch is provided and in addition a further half link circuit having the connector portion only is provided. 50 Although the switches are of the 12-point type, position 1 is utilised as the home position and position 12 is not used, the remaining ten positions, to which the connector switch can be set by the dialling of a single digit, serving ordinary subscribers, coin box subscribers, party line 55 groups of subscribers (one set of contacts being allotted to each party line) and one outgoing junction to an adjacent R. C. X. It will be understood that the board at the adjacent R. C. X. may be similar to that shown except that it is not 60 wired for tandem facilities.

Before proceeding with the general circuit description of the board, it will be convenient to consider the operation of the all-relay ringing 65 current and tone generating equipment of Fig. 11. When the equipment is taken into use so that ringing current and tone may be required, earth is applied to the common ringing start lead 13 whereupon relays RC and RT operate in series. The former at armature $rt1$ inserts its upper winding in series with the lower winding and since the two windings are arranged in opposition to one another, relay RT then releases. Thereupon the cycle of operation is repeated as long as the earth is maintained on the lead 13

thereby producing a tone of definite frequency in the transformer T2. At armature $rc1$ the vibrator RV is set into operation and produces an alternating current for ringing purposes in the left-hand winding of the transformer T3 in well-known manner. At armature $rc2$ earth is connected to relay IR, which is shunted by the high capacity electrolytic condenser QG. This relay operates in series with resistance YO after a delay represented by the charging up time of the condenser, and at armature $ir1$ operates its relief relay IRA. At armature $ir2$ the low resistance YP is bridged across the winding of relay IR and condenser QG so that relay IR releases and the condenser is discharged. Relay IR on releasing again connects up the condenser charging circuit and releases relay IRA and the cycle of operations is now repeated. By this means relay IRA is pulsed at a definite slow rate so as to provide an interrupted ringing current supply to common lead 16 and an interrupted ringing current supply to common lead 12 by way of armatures $ira1$ and $ira2$ respectively. 10 15 20 25

When busy tone is required, earth is applied to common lead 10 whereupon relay BZ is energised and de-energised at a predetermined rate in series with the impedance BC in the same manner as relay RT is operated in series with relay RC so that a tone at a frequency corresponding to the usual busy tone is produced in transformer T4. The start earth over common lead 10 also extends to relay XB which is slow to operate and release and on operating energises relay ZB which is also slow to operate and release. This relay in turn at armature $zb1$ short-circuits relay XB which therefore releases and in turn short-circuits and releases relay ZB. The two relays thus interact and at armature $zb2$ the busy tone supply to common lead 11 is interrupted to give the usual well-known busy indication. 30 35 40 45 50 55 60 65 70 75 80 85 90 95 100

A ringing return battery is connected to common lead 15 while the lamp RR inserted in the continuous ringing current lead 17 serves to limit the current flow taken from the generator to a value suitable for application to the junction. 45 50 55 60 65 70 75 80 85 90 95 100

The fuse alarm relay FA connects over lead 14 with the fuse alarm bar and is therefore operated if a fuse blows. It then lights the fuse alarm lamp FAL and operates the alarm bell AB, facilities being provided to cut these out of circuit 50 if so required by means of the key KAC. Relays TT and TN serve as a test number circuit which together with a further function of relay FA will be dealt with later in the description.

Considering now the general circuit operation 55 of the board, it will be assumed that the circuit shown is wired for use at a tandem R. C. X. and that a call is originated by an ordinary local subscriber. This is effected either by turning a hand generator or by lifting the receiver to loop the 60 line according to whether the telephone instrument is of the magneto or the central battery type. In the former case as the line relay R is to respond to alternating current, it is connected across the line by way of the condenser QA, while 65 in the latter case the condenser and the dotted connections are omitted and the battery and earth connections shown by lines intercepted by circles are provided. In either case relay R is operated and locks over its right-hand winding 70 over lead 20 in series with the common finder start relay FS, assuming that the link circuit is disengaged. Relay FS thereupon at its armatures $fs1$ and $fs2$, Figs. 1 and 2, completes testing and hunting circuits for the line finder switch 75 80 85 90 95 100

which is set in operation to hunt for and connect with the calling line.

Testing is now made for battery potential which marks the calling line and if the wipers of the switch are not standing on the calling line, the test wiper LF1 will not encounter a battery potential so that relay GF will operate in series with the upper winding of relay FF, the winding of relay GF being of high resistance so that relay FF will not operate in this condition. Relay GF at armature *gf1* energises the magnet LFM which thereupon opens its interrupter contacts *fm* and releases relay GF so that the magnet is now de-energised and in so doing advances the wipers to the next set of contacts. The magnet LFM and relay GF continue to interact and advance the wipers step by step until the contacts associated with the calling line are reached when wiper LF1 will encounter battery potential by way of armature *r2* and the cut-off relay K and resistance YA in parallel. Under this condition relay GF is shunted and cannot re-operate but relay FF operates over its two windings in series and at its armature *ff1* applies guarding potential by way of its low resistance lower winding to wiper LF1, this circuit serving to hold relay FF operated and also to operate the calling subscriber's cut-off relay K. A circuit is now completed over armatures *br1* and *ba1*, Fig. 7, lead 21 and armatures *fs3* and *rb1* to operate the slow to release relay RA and this relay in turn operates relay RB. Relay RB thereupon at armature *rb1* locks and disconnects relay RA and during the operated period of relay RA the calling signal is repeated in the form of a pulse of ringing current over the junction extending to the main exchange to signal the operator at the manual board. Ringing current is transmitted from common lead 17 by way of armature *ra2* to the positive junction conductor, the ringing current generator having been started up on the operation of relay FS when earth was applied over armatures *fs6* and *ba8* to the common ringing start lead 13.

In the area described in the previously mentioned specification, this tandem R. C. X. board is connected to the main exchange by way of a so-called tandem satellite exchange and accordingly it will be understood that the ringing pulse is received at the tandem satellite exchange and is repeated from there to the main exchange after having brought about the selection of a free junction from the tandem satellite to the main exchange.

Returning again to the operation of the relays FF and K on the finding of the calling line, relay K at armatures *k1* and *k2* disconnects relay R from across the line conductors, at armature *k3* opens the start circuit and at armature *k4* locks up and disconnects resistance YA from across its own winding, the purpose of this resistance being to increase the operating speed of relay FF so that the driving circuit may be efficiently broken when the calling line is reached. Relay FF at armature *ff1* disconnects relay GF and at armatures *ff2*—*ff6* connects the wipers of the finder switch through to the link circuit. At armature *ff7*, Fig. 6, the finder start relay FS is disconnected from the start lead 20 but it is maintained energised over armatures *rb2* and *fs4*. The busy tone relay BT is connected to the start lead in its place so that if any other subscriber calls while the link is engaged, this relay will be operated in series with the calling line relay and at armature *bt1* applies earth to the common busy tone

start lead 10 so that busy tone is extended from the busy tone lead 11 through the windings of relays BT and R to the calling line to inform the calling party that the link is engaged.

In order to distinguish between calls originated by a local subscriber and by a subscriber in the adjacent R. C. X., contacts in the line finder bank LF4 which represent local subscribers are earthed so that in the present instance relay RS is operated and at its armatures *rs1*, *rs2* and *rs3*, 10 Fig. 2, connects battery feed by way of the windings of relay FI across the calling subscriber's loop. Relay FI now operates and prepares an operating circuit for relay DD, Fig. 3.

When the operator plugs into the calling junction relay A, Fig. 7, is operated over its upper winding in series with the differential relay OC, and at armature *a2*, Fig. 3, operates relay B. Relay B at armature *b2* operates relay BA and at armature *b3*, Fig. 6, extends the lower junction 20 lead through to relay A, this relay now remaining held over its two windings in series. The battery potential via resistance YJ is disconnected from the negative conductor at the same armature, this circuit normally serving for the purpose 25 of charging the R. C. X. battery from the main exchange. The differential relay OC which may have momentarily operated over its upper winding on the initial operation of relay A now releases and its operation produces no undesired 30 effect. Relay BA at armature *ba6* completes a circuit for relay DD by way of armatures *vn5* and *fl1* and this relay at armature *dd3*, Fig. 4, operates relay DR which at its armatures *dr1* and *dr2*, Fig. 7 gives reverse battery supervision to the 35 operator to indicate that the calling subscriber is on the line. This arrangement is necessary to cover the case in which a subscriber originates a call and cannot gain access to the operator due to the fact that the link is engaged. He receives busy tone in these circumstances as previously mentioned and will then hang up his receiver. Since however his line relay R remains locked up when the link becomes free the call is automatically extended to the operator. In this 40 case however, relay FI will not be operated and this will be indicated by the absence of the reverse battery supervision given by the operation of relay DR. The operator will now ring the calling subscriber by operating a key which extends an unbalance signal over the junction, for example by the connection of earth potential to both the negative and positive conductors, whereupon the differential relay OC operates in series with relay A which remains energised. Relay OC 45 thereupon at armature *oc1*, Fig. 3, earths lead 35 and so operates the slow-to-operate relay RF, Fig. 5, which at armature *rf1* applies earth to the ringing start lead 13, and at armatures *rf1* and *rf3*, Fig. 1, extends ringing current from 50 common lead 17 over the line finder wipers to the calling line.

The operator converses with the calling party and takes particulars of the call required and requests the calling party's number in addition to 55 the wanted party's number in case it is required to record a fee against him.

If this is so, the operator may wish to verify the correctness of the number which the calling party has given as his own, and she accordingly 60 dials back over the junction into the link circuit taken into use by the calling party and sets the connector portion of the link on to the calling party's line. The digit dialled by the operator is received on relay A and on each release 75

of this relay earth is extended over armatures br_2 , a_2 , cc_2 and b_1 to relay C and in parallel therewith over armatures h_4 , by_1 and ba_3 to the connector switch magnet CSM. The wipers of this switch are accordingly set on to the calling line, relays B and C holding operated during the impulse train due to their slugs.

At the end of the train, relay B remains held while relay C releases after its slow release period.

- 10 Since the line to which the wipers have been set is an ordinary local one as distinct from a party line or line from an adjacent R. C. X., the particular conditions required in the link circuit are set up by providing a strapping connection from
- 15 the relevant contact on the CS5 bank, Fig. 4, to terminal LOC so that relay CR is operated on the release of relay C at the end of the train. Relay CR thereupon at armature cr_4 , Fig. 3, prepares a circuit for relay DD for the supervision
- 20 of the called party, the original operating circuit for this relay having been disconnected at armature vn_5 on the operation of the connector switch off-normal relay VN over wiper CS6 (Fig. 4) when the connector switch is stepped off-normal.
- 25 Relay DD however holds operated over armatures c_3 and dd_1 until the end of the dialled impulse train. Relay ID, Fig. 4, which was operated by relay BA is also held during the train and at its armature id_1 , Fig. 2, short-circuits
- 30 armature a_1 to prevent it from giving a succession of clicks to the calling party.

Since the line to which the connector wipers have been set will be engaged, the operator will now receive a busy tone. Relay C at armature c_2 operates the slow-to-release relay E and at the end of the train these two relays release in sequence, and while relay E remains up a circuit is completed over armatures e_4 and c_5 for relay H. If this relay fails to operate due to the called

- 40 line being busy, on the release of relay E a circuit is completed over bank and wiper CS6, Fig. 4 and armatures ba_5 , e_2 , h_5 and hr_8 to operate relay BY. Relay BY at armature by_4 , Fig. 3, connects up the busy tone lead 11 via lead 30, armature ca_4 and lead 39 to the upper winding of relay A from whence the tone is induced in the other two windings and applied in a balanced circuit to the incoming junction and so to the operator.

- 50 If the operator wishes to check the number further, she may now operate a trunk offering key which unbalances the lines to bring in again the differential relay OC. Since the connector has been set, that is to say relay BN is operated,
- 55 the operation of armature oc_1 now extends an earth by way of armature cc_1 , lead 35 and armature vn_4 to operate relay RC. Relay RC completes a circuit from earth, armature ba_4 , Fig. 4, lead 36, armatures ha_2 , rc_3 and bp_2 to operate
- 60 relay HR over its left-hand winding and this relay at armatures hr_3 and hr_4 Fig. 4 connects the operator through to the busy line, the connection to the same party over the finder side of the bank being opened at armatures hr_5 and hr_6 .
- 65 Relay HR also at armature hr_8 releases relay BY whereupon busy tone is removed and relay HR is enabled to lock up over its right-hand winding.

- 70 After having spoken to the subscriber and verified that he is actually the calling party, the operator must clear down the connector half of the link and this she does by throwing her identification release key which has the effect of applying a high voltage pulse to the junction which
- 75 causes the neon tube NL to strike, the polarity

of the pulse being such that current flows in a direction for which rectifier MRB is conductive, and hence relay TO operates. Relay TO at armature to_1 , Fig. 7 completes a circuit over armature rs_5 to operate relay BR which at armature br_1 locks up in series with relay FS dependent upon armature vn_6 and at armature br_2 Fig. 3, releases relays B and BA in turn, whereupon at armatures ba_3 and ba_5 homing circuits are completed for the connector switch in conjunction with the interacting relay GC. Relays CR and HR which are held operated dependent on relay BA are also restored to normal. Relay BR releases when the switch reaches normal or when the operator releases the key if it is still operated at this time and relays B and BA then again operate.

Assuming that the required party is also a local subscriber, the operator now proceeds to dial his number thereby positioning the connector wipers on his line which is given an immediate ring followed by intermittent ringing. Considering the operations during the impulse train, relays B, BA and C are held operated, while relay VN is again operated as soon as the connector switch moves off-normal. Relay C at armature c_2 operates relay E which in turn operates relay ER. At the end of the impulse train relay C releases as already described and disconnects relay E, earth now being extended from armature ba_4 , Fig. 4, lead 36, by way of armatures by_2 , e_4 and c_5 through the windings of the switching relay H in series and armature pr_1 to the test wiper CS3.

If the calling party is disengaged, battery potential by way of the winding of his cut-off relay K will be encountered so that relay H will operate. Relay H thereupon at armature h_1 short-circuits its right-hand winding and so applies low resistance earth to the test wiper for guarding purposes. At armatures h_6 and h_1 , Fig. 4, a circuit is completed for ringing the wanted party's bell and it will be seen that as long as relay ER remains operated, continuous ringing will extend by way of common lead 17, armature er_1 and the upper winding of the ring trip relay F to the negative line, a return path being found over the positive line to the ring return battery by way of resistance YE and common lead 15. The wanted subscriber thus receives an immediate ring and on the release of relay ER following that of relay E the interrupted ringing lead 16 is connected up in place of the continuous ringing lead 17. Relay DD was again operated on the re-energisation of relay BA but is released on the release of relay C and is now under the control of relay CI for supervising the called party.

On the reply of the called party the ringing is tripped by the operation of relay F which at its right armature f_1 removes the short-circuit from its lower winding over which it operates fully in series with resistance YF to earth by way of armatures rc_1 , vn_2 and ba_4 . Relay F extends the operator's circuit through to the wanted party at armatures f_2 and f_3 , Fig. 4, a battery feed to this party being connected up from earth over armature hsr_2 , Fig. 3, upper winding of relay CI, lead 26, armatures fl_1 , pr_8 , hsr_4 , cb_1 , a_1 , sw_5 , cb_2 , cr_2 , f_3 and h_6 to the positive connector wiper CS2 and from battery via resistance YD, Fig. 3, 70 armature hsr_3 , lower winding of relay CI, armature sw_7 , lead 28, armatures hr_4 , f_2 and h_1 to the negative wiper CS1. Relay CI thereupon operates and at its armature ci_1 completes a circuit over armature cr_4 to re-operate relay DD 75

which in turn operates relay DR, Fig. 4, to give supervision to the operator that the called party is on the line. The two subscribers are now connected via the link circuit, battery feeds being supplied to the calling and called parties by relays FI and CI respectively. The operator withdraws from the connection by removing her plug, whereupon relay A releases and in turn releases relay B. Relay BA however remains held from earth over armatures $h3$, $fi3$ and $ba1$ and so maintains holding circuits for relays FS, H, F and CR. Release of the link circuit is thus under control of the calling party and when he subsequently hangs up, relay FI releases and releases relay BA which in turn releases all the various relays operated and brings about the homing of the connector switch in the manner already described. If the wanted party is busy relay BY is operated as in the case of the verification connection and busy tone is returned to the operator. She will then inform the calling party who will replace his receiver thus releasing relay FI. The operator will then remove her plug to permit relays A, B and BA to fall away so that release take place in the usual manner.

In case the call is intended for a party line on the same exchange, the wipers of the connector are set by the digit dialled to a distinctive position where relay PR, Fig. 4, is operated on. The release of relay C over the CS5 wiper and bank and cross-connection to terminal PL. Relay PR upon operating at armature $pr4$ locks up to earth at armature $ba4$, at armature $pr1$ operates relay CR and at armature $pr6$ removes the short-circuit from the lower winding of the ring trip relay F, armature $er2$ being operated at this time since relay ER remains held for a short interval after the release of relay C. If the line is free, relay H operates in the usual manner and a circuit is then completed for relay ED, Fig. 5, from earth by way of armatures $ba4$, $vn2$, $f5$, $h2$, $pr1$ and $er3$. On the release of relay ER, relay ED remains locked to this earth by way of its armature $ed1$. Relay ED also at armature $ed3$ completes a circuit for repeating the succeeding digit in the form of earth impulses over the positive connector wiper and bank CS2 so as to cause equipment associated with the party line to bring about the selection of the required party. This circuit extends from earth, armature $ed3$, Fig. 2, armatures $pr8$, $hsr4$, $cb1$, $a1$, $sw5$, $cb2$, $cr2$, $f3$ and $h6$ to the positive wiper CS2 and thence to the party line equipment. Relay A in responding to the next digit selects the required party on the party line, the impulses being repeated by armature $a1$. During this impulse train relay RC is operated over armatures $c4$ and $ed2$ and at armature $rc2$ opens the circuit of relay ED which however remains held until the end of the train. When relay E releases, the circuit of relay F is opened at armature $e3$ and it de-energises to initiate the ringing operation. Relay RC is at armature $f5$ now released and again prepares the locking circuit for relay F at armature $rc1$ and the call proceeds in the normal manner.

If the call is intended for a subscriber at the adjacent R. C. X., the wipers of the connector will be set to a position in which the bank contact of wiper CS5 will be strapped to terminal OGJ. Relay HS is accordingly operated on the release of relay C and at armature $hs1$ locks itself up and operates relay HSR which at armature $hsr1$ removes the short-circuit from the lower winding of relay F. Relay F operates and thereupon a loop is completed across the out-

going conductors to the adjacent R. C. X. to prepare the distant equipment to respond to further digits dialled by the operator. This loop extends as follows: negative connector wiper CS1, armatures $h1$, $f2$ and $hr4$, conductor 28, armature $sw1$, lower winding of relay CI, armature $hsr3$, lower winding of shunt field relay CD, upper winding of relay CI, conductor 26, armatures $hsr4$, $cb1$, $a1$, $sw5$, $cb2$, $cr2$, $hsr5$, $f3$ and $h6$ to the positive connector wiper CS2.

When the operator dials the next digit, relay A responds in the usual manner and at armature $a1$ repeats the impulses forward to the adjacent R. C. X. During each impulse train relays C, E and ER are operated and hold in the usual manner and at armature $e5$, Fig. 3, relays CI and CD are short-circuited so as to give an impedance-free impulse repeating loop. At the end of the impulse train when relays C, E and ER restore, relays CI and CD are again bridged across the line for supervision purposes from the distant R. C. X. When the wanted subscriber answers, battery is reversed back over the junction in the usual manner to bring about the operation of relay CD which at armature $cd1$ operates relay DD which thereupon operates relay DR to give the required supervision to the operator and also at armature $dd2$ short circuits the impulse contact to prevent the connection to the adjacent R. C. X. being released when the operator subsequently withdraws her plug. When this is done the two parties are left locally connected together by way of the junction between the two R. C. X.'s.

Considering now the case in which the call is from a party line subscriber to another party on the same line, a calling signal is given to the manual board as before and the line finder hunts to locate the calling party's line. It should be explained that contacts in the line finder bank LF5 which represent party lines are cross-connected to corresponding contacts in the connector bank CS4, Fig. 5. Consequently since the subscriber required is on the same party line as the calling subscriber, when the operator dials back over the junction and sets the connector half of the link into engagement with the same line as is calling, relay PRR, Fig. 1 is operated by way of armature $ff5$, bank and wiper LF5, cross connection to CS4 bank and wiper, armature $pr3$ to earth, relay PR, Fig. 4, being operated since the connector switch CS to set on to a party line. The operation of relay PRR at its armature $pr1$, Fig. 5, brings about the operation of relay H over its right hand winding on the release of relay C regardless of the fact that the selected line tests busy so that the operator is connected directly to the busy line. A further digit is now dialled which is repeated from the link circuit in the form of impulses into the selected party line equipment in the manner already described and thus causes the wanted party to be connected in parallel with the calling party. On a revertive call the calling party line subscriber is instructed to hang up after giving particulars of the wanted party to the operator so that when the operator completes the dialling operation and ringing current is applied to the party line, both calling and called parties' bells are rung. When the called party answers, ringing is tripped thereby indicating to the calling party that the call has been answered whereupon he also removes his receiver and the two parties can then commence conversation. The operator now withdraws from the connection and the junction to the tandem

R. C. X. is released, the link taken into use being maintained throughout conversation.

Consider now the case in which a call is originated in the adjacent R. C. X. which is connected to the main exchange by the tandem R. C. X. in which the equipment shown is located. The line relay R will be operated over the junction from the adjacent R. C. X. whereupon the main exchange operator will be signalled in the usual manner, and a finder switch will be caused to hunt for the calling junction which appears in its banks in the same way as a subscriber's line. On the completion of the finding operation, the connection is switched through and the operator takes particulars of the calling and wanted parties' numbers. She may now if she desires set up a verification connection and for this purpose will dial the number of the calling party which will result in impulses being transmitted back over the junction to the adjacent R. C. X.

The contact in the bank LF6 corresponding to the junction is wired to terminal J, Fig. 4, and consequently when the finder completes its operation relay HS is operated but not relay HSR as it is now short circuited.

The operator first dials the digit corresponding to the adjacent R. C. X. and the connector wipers are set accordingly and encounter a busy condition but tone is not transmitted back owing to the operation of armature *hs4*. Relay ID is now released so as to render the impulsive armature *a1* effective and the succeeding train of impulses is repeated over the junction to operate the connector portion of the link in the R. C. X. The impulse repeating circuit extends as follows: negative line, Fig. 1, bank and wiper LF3, armatures *ff2*, *rs4* and *sra1*, upper winding of relay FI, armature *rs1*, winding or polarised relay FD, lower winding of relay FI, and armatures *rs3*, *cr3*, *hsr6*, *cbl*, *a1*, *sw5*, *cb2*, *cr2*, *hsr5* and *ff3*, wiper and bank LF2 to the positive line. The relays FI and FD are short-circuited during dialling by the low resistance YC and armature *er4* in the usual manner to give an impedance-free loop.

If the number has been correctly given, the operator will receive a busy signal. This in the circumstances is considered a sufficient check and provision is not made for the operator to cut in on the line.

To release the verification connection set up at the adjacent R. C. X., the operator operates relay TO by extending a high voltage signal as already described, but this time since relay RS will be unoperated owing to the fact that a junction has initiated the call at the tandem R. C. X., relay TO at armature *to1* operates relay SRA instead of relay BR. Relay SRA at armatures *sra1* and *sra2* completes a metallic connection from the main exchange junction through to the calling R. C. X. junction and so extends the high voltage signal through to the calling R. C. X. to bring about the necessary release. During this time delay A is disconnected from the line and a local holding loop is provided over armature *sra3* and resistance YK, while at armature *sra4*, Fig. 2, relays FI and FD are disconnected from the line. At the conclusion of the pulse relays TO and SRA restore and the operator may now set up a connection to the wanted party by dialling his number in the adjacent R. C. X.

When the wanted party answers, the polarised relay FD is operated as a result of the reversal of current over the calling junction in the usual

manner and operates relay DD, Fig. 3, which in turn operates relay DR, Fig. 4 to give supervision to the operator. The operator now withdraws from the connection and frees the junction to the tandem R. C. X., whereupon relay A restores and opens the loop across the junction to the calling adjacent R. C. X. so that this junction is also freed and the two subscribers on the calling adjacent R. C. X. are therefore linked together locally. The release of relay A also restores the equipment of the tandem R. C. X. board to normal, relay BA not being held in this case over armatures *h3* and *f3*.

In the case of an incoming call from the main exchange to the R. C. X. the operator takes into use the main exchange junction and dials the required number and the connector half of the link establishes connection with the wanted party who is rung in the usual manner. In case, however, he should be busy, the operator will receive the usual busy signal owing to the operation of relay BY and if the incoming call is for example a long distance call, the operator may wish to cut-in on the busy connection and offer it. This she does by operating her trunk offering key which unbalances the line and brings about the operation of relay OC and in turn relays RC and HR, Fig. 5 as before. On the release of relay OC when the operator restores her key, relay RC also releases but relay HR remains locked over its right-hand winding and armature *hr1*, and hence relay BP is now operated from earth by way of armature *ba4*, lead 36, armatures *ha2*, *rc3* and *hr2*, winding of relay BP to battery. Relay BP at its armature *bp3* extends earth from lead 36 over armatures *by2*, *bp3* and *c5* to the windings of relay H in readiness for the subsequent operation of this relay. If the incoming call is accepted, the subscribers in conversation are asked to restore their receivers. The operator again depresses her trunk offering key which again operates relay OC and in turn relay RC and this time the operation of relay RC extends earth over armatures *rc3*, *bp2*, *rs6*, *vn3*, *pr5* and *hr1* to the test wiper CS3 to bring about forced release of the existing connection in case the unwanted party should attempt to hold it by not hanging up. At the end of the pulse relays OC and RC release and relay H now operates over its two windings in series to the wanted party's cut-off relay and this party is now rung in the normal manner via the ring trip relay F.

In case the call had been extended to an adjacent exchange, relay OC upon operating as a result of the unbalancing of the lines would have operated relays RC and HR as before and since in these circumstances relay HS would be operated, the unbalance signal would be repeated by way of armatures *rc4*, *hs2* and *hr3* over the junction to the adjacent exchange to bring about cut-in to the engaged line. It will be seen that on a call of this nature, since relay BA is operated without the operation of relay FS, relay OE is operated over armatures *ba9* and *fs1* and at armature *oe1* connects up relay BT to busy the link to calling parties.

Further consideration will now be given to the conditions when two subscribers are in conversation on a call local to the tandem R. C. X. or between a tandem R. C. X. subscriber and an adjacent R. C. X. Subscriber and the operator withdraws her plug. Relay A then releases and in turn releases relay B and relay BA remains held over operated armatures *h3*, *f3* and *ba1* as

previously described. A circuit is now completed for relays CA, CB and CC in series from earth via armatures *b2* and *ba2*. These relays upon operating switch the incoming junction over to the additional half link circuit which comprises a connector portion only so that a further incoming main exchange call may be completed even though the ordinary link is engaged. The actual switching over of the junction is accomplished by the armatures *ca1*—*ca4*, Fig. 8, while armatures of relays CB and CC switch over the impulsive and other circuits in association with the junction into cooperation with the second half link. This half link is to all intents and purposes identical with the connector side of the ordinary link, certain features which are not required being omitted, for example, relay RF which is only required in connection with re-ringing a calling party is not included in the second half link as it will never be required. The relays in this half link may be distinguished from those of the connector side of the ordinary link by virtue of the fact that they are designated *1B*, *1BA*, *1C*, etc., their functions however being identical with those of the relays *B*, *BA*, *C* already described. If this additional half link is in use on an incoming main exchange call and the ordinary link is freed, there will be no interference with the main exchange call since relays CA, CB and CC remain held over lead *33* from armature *1b3* in the additional half link.

In case it is desired to give a discriminative signal when a coin box subscriber originates a call, this may be effected by arranging to operate a relay over an additional finder bank and wiper, this relay upon operating causing a distinctive ringing signal to be extended over the junction. The necessary discrimination could be effected by applying normal ringing current to the junction when an ordinary subscriber calls and applying ringing current via a half wave rectifier to the junction when a coin box subscriber calls.

In areas of the type described, it will be appreciated that it is very desirable to be able to perform a centralised testing of all subscriber's lines in the various exchanges from the main exchange and arrangements are made whereby a test clerk may set up a connection to a subscriber's line in the normal manner and may then by applying to the junction a high potential pulse of reverse polarity to that required for verification release purposes bring about the removal of all transmission bridges from across the speaking leads and the bypassing of the bridge condensers so as to give a through metallic loop. On the reception of such a pulse at the tandem R. C. X. after a connection has been set up to a line connected to the tandem R. C. X. the neon tube NL, Fig. 6, strikes and the resulting current flow will be in a direction to which rectifier MRA is conductive and hence relay TC now operates. This relay at armature *tc1*, Fig. 2, operates relay TS which at armature *ts1* prepares a circuit for relay SW.

At the end of the high voltage pulse, relay TC restores and a circuit is then completed for relay SW in series with relay TS which remains held. Thereupon at armatures *sw3* and *sw4*, Fig. 7, relays A and OC are disconnected from the junction and the bridge condensers QD and QC are short-circuited. A local holding circuit is completed for relay A over armature *sw2* and resistance *YK* so as to maintain the connection while relays CI and CD are disconnected at armatures *sw5* and *sw1*.

The test clerk is now in direct metallic connection with the desired subscriber's line, and since relays F and H will have been already operated on the reply of the subscriber, the only apparatus connected to the line at the R. C. X. is the neon tube NL and its associated responding relays. Since however this tube in its normal condition offers substantially infinite resistance, its effect on the testing of the line may be neglected.

On the completion of the testing, the test clerk causes the same high voltage potential to be re-applied to the junction in order to restore the common equipment to its original condition. Again relay TC is operated thereby releasing relay TS but holding relay SW over its lower winding and armature *sw1*. At the end of the pulse, relay SW releases also and relay A in the common equipment is re-connected to the junction. The connection may subsequently be released in the usual way by disconnecting the loop to relay A whereupon the R. C. X. equipment is freed for use on further calls.

In case the line to be tested is connected to the adjacent R. C. X., relay SRB is operated over lead *22* in addition to relay TS. On the operation of relay TC since terminals *18* and *19* are strapped as the exchange has tandem facilities and relay HS is operated. Relay SRB at armatures *srba1* and *srba2* short-circuits condensers QC and QD immediately so as to relay the high voltage pulse to the adjacent R. C. X. and at armature *srba3* holds relay A. On the operation of relay SW when the pulse ceases, relay SRB is released at armature *sw6*. When a further pulse is received for restoring conditions to normal, relay TC again operates and releases relay TS while holding relay SW. The pulse is therefore relayed to the adjacent R. C. X. and relay SRB cannot now operate as its circuit is opened at armature *sw6*. At the end of the pulse relays TC and SW release and conditions are restored to normal.

The rectifiers MRC and MRD in circuit with relay A serve to prevent a high voltage pulse from circulating through the exchange battery via its windings in series.

In case it is desired to check the correct functioning of the R. C. X. board from the main exchange, the operator dials a so-called test number whereupon the connector side of the link is set into association with the test number relays TT and TN in the equipment of Fig. 11. Relay TN is thereupon operated over the P lead in series with relay H and the lefthand winding of the retard TT serves to trip the ringing and so operate relay F. The operator will now be connected through. Relay TN at armatures *tn2* and *tn3* starts up the busy tone and ringing equipments by earthing leads *10* and *13* respectively. Hence if the equipment is working correctly the operator will receive a continuous tone at the frequency of the ordinary busy tone which is extended from the transformer *T1* and via armatures *fa3* and *tn1* to the right hand winding of retard TT whence it is extended by induction over the line to the operator. In case a fuse should be blown, relay FA will be operated as already described and at armature *fa3* it connects up the ringing tone transformer *T2* in place of the busy tone transformer *T1*. The operator will therefore receive an inverted ringing tone, that is to say, the ordinary on and off periods are reversed since the connection is made via the back contact of armature *ira2*. The operator is thus

informed as to the condition of the equipment and this facility is particularly useful in the case of unattended boards.

The relay TH which is very slow to operate and 5 may be of the thermostat or dash pot type comes into action if the finder switch is set in operation and owing to some defect fails to find the calling line. Thereupon at armature *th* relay FS is disconnected but remains held over its lower winding. 10 When the operator plugs in she will find no one on the line and will attempt to ring the calling party. This will be impossible owing to the non-operation of relay FF and when the operator removes her plug relays BA, FS and TH will all 15 release. If the calling line is common battery operated, a call will again come in and the procedure will be repeated assuming the fault has not cleared itself automatically. The operator will then realize that there is trouble at the tandem R. C. X. and will take steps to have it dealt with.

We claim:

1. In a telephone system including a plurality of exchanges, means including a trunk line for 25 interconnecting said exchanges in tandem, a source of high voltage at one of said exchanges, means for connecting said source to said trunk line, a relay and a gas discharge tube connected in series at another of said exchanges operated in 30 response to the connection of said high voltage source to said trunk line, feeding bridges and transmission condensers in said other exchange normally effective for completing the talking circuits for established connections in the said other 35 exchange, and means operative in response to the operation of said relay for cutting out said feeding bridges and said transmission condensers and for extending said high voltage source over the connection to a further exchange to effect a 40 switching operation thereat.

2. In a telephone system including a plurality of exchanges, lines terminating in one of said exchanges, a trunk line extending from said one exchange and terminating in an operator's position at another of said exchanges, a calling line and means for automatically connecting said calling line to said operator's position by way of said trunk line, automatic switches in said one exchange controlled over said trunk line from said 45 operator's position for setting up connections to said lines, feeding bridges and transmission condensers at said one exchange normally included in the connections established to line in said one exchange, testing means at said operator's position for permitting the operator to test the connected lines in said one exchange over said trunk line, said testing means including means for connecting a pulse of high voltage to said trunk line, a relay and a gas discharge tube connected in 50 series in said one exchange, said relay and gas tube being unresponsive to normal current flow in an established connection but responsive to said pulse of high voltage to cause operation of said relay, and means controlled by the operation 55 of said relay for cutting out said feeding bridges and condensers to establish a metallic loop between the operator's position and the connected line for testing purposes.

3. In a telephone system, a plurality of exchanges, a control exchange connected in tandem with said plurality of exchanges, an operator's position in the control exchange, lines terminating in said plurality of exchanges, means including said operator's position for establishing 70 a connection to a called one of said lines in any 75

one of said connected exchanges, feeding bridges and transmission condensers providing the talking circuits included in said established connection, means at said operator's position for transmitting a high voltage signal of one polarity or the opposite polarity to said established connection, relay means and a gas discharge tube connected in series included in said established connection, said relay means and said gas discharge tube being unresponsive to normal current flow 1 but responsive to said high voltage signal to cause the operation of said relay means, and means controlled by the operation of said relay means for cutting out feeding bridges and said transmission condensers in said established connection 1 or for releasing said established connection dependent upon the polarity of said high voltage signal transmitted to said connection.

4. In a telephone system, a plurality of exchanges, an operator's position in one of said exchanges, lines terminating in the other exchanges, means responsive to the initiation of a call from a line in any one of said exchanges for automatically connecting said calling line to said operator's position, numerical switches in the 2 exchange terminating said calling line operated by the operator over said original connection to extend a verification connection to the calling line to verify the number given by the calling party as his own, means for transmitting a high 3 voltage signal over said original connection, a relay and a gas discharge tube connected in series included in said original connection, said relay and gas discharge tube being unresponsive to normal current flow but responsive to said high 35 voltage signal to cause the operation of said relay, and means controlled by the operation of said relay for releasing only said numerical switches included in the verification connection without releasing said original connection whereby said 40 numerical switches may be used to set up a connection to a called line.

5. In a telephone system, a first and second exchange, lines terminating in the second exchange, control and switching apparatus in the second exchange for completing connections to said lines, one of said lines interconnecting said exchanges and terminating in said control and switching apparatus, feeding bridges and transmission condensers associated with said control and switching apparatus and normally effective for completing the talking circuits for established 50 connections between said lines, a source of high voltage at the first exchange, means for connecting said source to said one line interconnecting said exchanges, a relay and a gas discharge tube connected in series in said control and switching apparatus, said relay and said tube being normally ineffective to normal current flow but effective in response to the connection of said source to said one line to operate said relay, and means controlled by the operation of said relay for cutting out said feeding bridges and said 55 transmission condensers.

6. In a telephone system, a plurality of exchanges, a control exchange connected in tandem with said plurality of exchanges, an operator's position in the control exchange, lines terminating in said plurality of exchanges, means including said operator's position for establishing 70 connections between said lines in any of said connected exchanges, feeding bridges and transmission condensers providing the talking circuits included in said established connections, means at said operator's position for transmitting a high 75

voltage signal of one polarity or the opposite polarity to an established connection to any one of said lines, a first relay and a gas discharge tube connected in series included in said connection being unresponsive to normal current flow but responsive only to said high voltage signal of said one polarity to cause the operation of said first relay, means controlled by the operation of said first relay for cutting out said feeding bridges and transmission condensers, a second relay and said gas discharge tube connected in series included in said connection being unresponsive to normal current flow but responsive only to high voltage signal of said opposite polarity to cause operation of said second relay, and means controlled by the operation of said second relay for releasing the connection to the called line in said established connection.

7. In a telephone system, a first exchange, a second exchange, lines terminating in said second exchange, an impulse repeater having a pair of speaking leads in the second exchange, a trunk line extending from the first exchange and terminating in said repeater in the second exchange, means for transmitting impulses from the first exchange over said trunk line to said repeater, a feeding bridge and transmission condensers associated with said repeater, said feeding bridge responsive to said transmitted impulses for repeating said impulses, means associated with said repeater responsive to said repeated impulses for extending the connection, a gas discharge tube normally connected across the speaking leads of said repeater, means operative only during the repeating operation for disconnecting said tube to prevent the striking of said tube in response to inductive surges created during the impulsive operation, means for transmitting a high voltage signal from said first exchange over said trunk line to said repeater to cause said tube to strike, and means operated in response to the striking of said tube for cutting out said feeding bridge and for short-circuiting said transmission condensers.

8. In a telephone system as claimed in claim 1 including means whereby the second connection of said high voltage source to said trunk line causes the re-insertion of said feeding bridges and transmission condensers.

9. In a telephone system as claimed in claim 5 including a test clerk's position in said first exchange and means for testing a line in the second exchange from said position effective in response to cutting out said feeding bridges and transmission condensers.

10. In a telephone system as claimed in claim 4 including means whereby the means for releasing said verification connection persists only as long as said high voltage signal is applied to said original connection.

11. In a telephone system as claimed in claim 3 wherein said relay means includes two relays and two rectifiers, said rectifiers being poled in opposite senses in their respective connections to said relays so that only one or the other of said relays is operated in accordance with the polarity of said high voltage signal.

12. In a telephone system as claimed in claim 4 including means at the operator's position for transmitting a signal by grounding both speaking

leads of the original connection to the operator, and means responsive to this signal for connecting a busy called line to the operator's position.

13. In a telephone system as claimed in claim 5 including means for temporarily disconnecting said gas discharge tube to prevent the striking of said gas discharge tube by the inductive surges produced during the extension of a connection to a called line.

14. In a telephone system, a distant exchange, 10 a tandem exchange, a trunk line interconnecting said distant and tandem exchanges, a main exchange, an operator's position at the main exchange, a control trunk extending from said position to said tandem exchange, subscribers' lines 15 terminating in said distant and tandem exchanges, means responsive to the initiation of a call by a calling line in said distant exchange for automatically extending an original connection from the calling line by way of said trunk line, said tandem exchange, and said control trunk to said operator's position, a numerical switch in said tandem exchange, a second numerical switch in said distant exchange, means controlled by the operator in case the operator desires to verify the number of said calling line for directly operating the numerical switch in the tandem exchange over said control trunk to connect with said trunk line interconnecting the distant and tandem exchanges and for then directly operating said 30 second numerical switch in the distant exchange over said control trunk, said first numerical switch, and said trunk line to connect with said calling line to verify the number given by the calling party, means thereafter controlled by the operator over said control trunk for releasing said first and second numerical switches while maintaining said original connection, said release of said numerical switches thereafter enabling said operator to directly control one of said 40 switches or both of said switches to extend a connection to a called line in said tandem or distant exchanges to connect the calling and called lines.

15. In a telephone system, a distant exchange, 45 subscribers' lines and toll trunks terminating in said exchange, a main exchange, an operator's position at the main exchange, a control trunk extending from said position to said distant exchange, means responsive to the initiation of a 50 call by a calling line in said distant exchange for automatically extending an original connection from the calling line by way of said control trunk to said operator's position, a numerical switch in said distant exchange, means controlled by the 55 operator in case the operator desires to verify the number of said calling line for directly operating said numerical switch over said control trunk to connect with said calling line to verify the number given by the calling party, means thereafter controlled by the operator over said control trunk for releasing said numerical switch while maintaining said original connection to the calling line, said release of said numerical switch thereafter enabling said operator to directly 60 control said numerical switch to extend a connection over one of said toll trunks to establish the desired toll connection for the calling line.

JOHN WILLIAM McCLEW.
